CLAIM

The ornamental design for a wireless charger with night light, as shown and described.

DESCRIPTION

FIG. 1 is a bottom, front and right side perspective view of a wireless charger with night light showing my new design; FIG. 2 is a top, rear and right side perspective view thereof; FIG. 3 is a front elevational view thereof; FIG. 4 is a rear elevational view thereof; FIG. 5 is a left side view thereof; FIG. 6 is a right side view thereof; FIG. 7 is a top plan view thereof; FIG. 8 is a bottom plan view thereof; FIG. 9 is a front and bottom perspective view showing the wireless charger with night light in a folded status; FIG. 10 is a bottom perspective view showing the wireless charger with night light in a state of use; and, FIG. 11 is a top perspective view showing the wireless charger with night light in a state of use. The broken lines in the drawings illustrate portions of the wireless charger with night light which form no part of the claimed design.

1 Claim, 11 Drawing Sheets
